GARMENT STRETCHER

Alexander C. McKenzie, Beaverton, Ontario, and
 Raymond H. Jones and Reginald J. Jones,
 Toronto, Ontario, Canada

Application February 26, 1946, Serial No. 650,246

7 Claims. (Cl. 223—69)

1

This invention relates to a garment stretcher comprising body and arm members especially adapted for use with sweaters and the like.

One object of this invention is to provide a strong and durable garment stretcher which can be inexpensively formed from wire.

Another object of this invention is to provide simplified means for hinging the arm members together.

Another object of this invention is to provide simplified means for supporting the garment stretcher on a peg or line, said means to be also adapted to lock the arm members in expanded or open position.

A further object of this invention is to provide improved means for adjustably mounting the body members on the arm members.

According to our invention we provide a garment stretcher consisting of body and arm forming portions. The arm forming portions comprise a pair of oppositely extending arms, one of said arms consisting of a transverse arm member and upper and lower arm members, the transverse arm member connecting the upper and lower arm members near their inner ends, and the other of said arms consisting of upper and lower arm members having loops at their inner ends hingedly mounting them on the transverse arm member, stops mounted at the inner end of the first arm adjacent the arm members of the other arm so as to limit the movement of the other arm, and a suspending-hook adapted to support and lock the arms in expanded position comprising a loop slidable along the transverse arm member, and extensions attached to the loop spaced apart from the transverse arm member and from each other and extending towards the upper arm members, said extensions being adapted to secure the upper stop and arm loop together when the suspending-hook is slid up the transverse arm member.

As a body forming portion we provide a pair of body members adjustably supported on lower arm members, the lower arm members having upwardly extending serrated members secured thereto, each of said body members being adjustably supported on a lower arm member by loop portions thereof, one loop passing around the serrated member and lower arm member and being adapted to rest in the serrations and the other loop being open and passing around the lower arm member, the first loop being substantially bent so that when the second loop is disconnected from the lower arm member the body

2

member hangs loosely and so that the second loop must be forced onto the lower arm member.

The novel features of this invention are shown in a preferred embodiment which will hereinafter appear in detail in the description that follows and are illustrated in the accompanying drawings in which similar reference characters indicate corresponding parts, and in which:

Figure 1 is a top plan view of the garment stretcher in expanded or open position showing in dotted lines a sweater applied thereto;

Figure 2 is a front elevation of Figure 1;

Figure 3 is a fragmentary front elevation showing the hinging arrangement of the upper arm members;

Figure 4 is a front elevation of a body member;

Figure 5 is a front elevation of the suspending-hook; and

Figure 6 is a fragmentary front elevation showing a loop of a body member secured on a serrated member.

Referring to the drawings, arm 1 consists of an upper arm member 2 and a lower arm member 3 which are integral. The arm members are formed at their inner ends into U-shaped stops 4 and 5 which are joined together by a transverse arm member 6. Transverse arm member 6 and a central bracing member 7 serve to hold the arm in the desired shape.

Arm 8 consists of integral upper arm member 9 and lower arm member 10. The arm members are formed at their inner ends into loops 11 and 12 which hingedly mount arm 8 on the transverse arm member 6. The loops pass between the arms of the stops 4 and 5 which closely limit the movement of the loops 11 and 12 along the transverse arm member 6; also when arm 8 is swung about arm 1 to bring the arms into the fully open position the stop members 4 and 5 contact the arm members 9 and 10 respectively and prevent the arm 8 from being swung past the fully open position.

To retain the arms in the fully open position a suspending-hook 13 is provided. It consists of a loop 14 which slides along transverse arm member 6 and extensions 15 and 16 which project from the loop. The longer extension 16 terminates in a hook 17 which can be used to support the garment stretcher on a peg, line or the like. When the suspending-hook is slid up transverse arm member 6, the shorter extension 15 passes behind arm member 2 and the longer extension 16 passes in front of member 9 securing the stop 4 and loop 11 together and there-

by locking arms 1 and 8 in the fully open position.

Fixed on the upper side of lower arm members 3 and 10 are serrated plates 18 and 18a having indicia representing various garment sizes marked thereon opposite the serrations.

Body members 19 and 20 consist of integral side members 21 and 22 and a transverse bracing member 23. The upper ends of each side of the side members 21 and 22 are formed into an open loop 24 and a closed loop 25. Closed loops 25 are bent at a substantial angle so that when loops 24 are forced upwards and hooked over lower arm members 3 and 10 they clamp loops 25 in position on the plates 18 and 18a. When loops 24 are disconnected, which requires an upward and outward movement, the body members hang loosely, away from the arm members, due to the angle of loops 25. The body members can then be adjusted by sliding loops 25 along serrated plates 18 and 18a until they rest in the serrations representing the desired size. The body members can also be slid off plates 18 and 18a onto lower arm members 3 and 10 and with loops 24 disconnected, swung up across the arm members, which can be disengaged from the suspending-hook and swung together almost to coincidence so that the whole device when folded occupies a very small space.

In use the arms are swung from the closed position into a partially open position and the ends of the arms are then inserted in a sweater 26 which is pulled over the arm members. The body members are then moved out the required distance apart along the lower arm members, within the sweater, as shown by the indicia on the serrated plate and secured thereto by loops 24 and 25. The arm members are then unfolded and locked in the fully expanded position by the suspending hook, as shown in Figure 1. The garment stretcher with the sweater mounted thereon is then suspended by hook 17 by a peg, line or the like.

As shown all the device, except the serrated plates 18 and 18a is made of heavy wire which is inexpensive and easily formed into the required shapes. Instead of serrated plates 18 and 18a, heavy serrated wires can be employed.

While the application has been described with respect to a particular embodiment it is not to be limited thereto but is to be construed broadly and limited solely by the scope of the appended claims.

What we claim as our invention is:

1. A garment stretcher comprising a pair of oppositely extending arms, one of said arms consisting of a transverse arm member and upper and lower arm members, the transverse arm member connecting the upper and lower arm members near their inner ends, and the other of said arms consisting of upper and lower arm members having loops at their inner ends hingedly mounting them on the transverse arm member, stops mounted at the inner end of the first arm adjacent the arm members of the other arm so as to limit the movement of the other arm, and a suspending-hook adapted to support and lock the arms in expanded position comprising a loop slidable along the transverse arm member, and extensions attached to the loop spaced apart from the transverse arm member and from each other and extending towards the upper arm members, said extensions being adapted to secure the upper stop and arm loop together when the

suspending-hook is slid up the transverse arm member.

2. A garment stretcher comprising a pair of oppositely extending arms, one of said arms consisting of a transverse arm member and upper and lower arm members, the transverse arm member connecting the upper and lower arm members near their inner ends, and the other of said arms consisting of upper and lower arm members having loops at their inner ends hingedly mounting them on the transverse arm member, stops mounted at the inner end of the first arm adjacent the arm members of the other arm so as to limit the movement of the other arm, and a suspending-hook adapted to support and lock the arms in expanded position comprising a loop slidable along the transverse arm member, and extensions attached to the loop spaced apart from the transverse arm member and from each other and extending towards the upper arm members, said extensions being adapted to secure the upper stop and arm loop together when the suspending-hook is slid up the transverse arm member, one of said extensions being relatively longer and having its free end formed into a hook for supporting the garment stretcher on a peg and the like.

3. A garment stretcher comprising a pair of oppositely extending arms, one of said arms consisting of a transverse arm member and upper and lower arm members, the transverse arm member connecting the upper and lower arm members near their inner ends, and the other of said arms consisting of upper and lower arm members having their inner ends formed into loops hingedly mounting them on the transverse arm member, the inner ends of the arm members of the first arm extending beyond the transverse arm member and being bent to form stop members containing the arm loops so as to closely limit their movement along the transverse arm member and being adapted to contact the arm members of the second arm so as to limit the motion of the second arm when it is swung about the first arm, and a suspending-hook adapted to support and lock the arms in expanded position comprising a loop slidable along the transverse arm member, and extensions attached to the loop spaced apart from the transverse arm member and from each other and extending towards the upper arm members, said extensions being adapted to secure the upper stop and arm loop together when the suspending-hook is slid up the transverse arm member.

4. A garment stretcher comprising a pair of oppositely extending arms, one of said arms consisting of a transverse wire arm member and integral upper and lower wire arm members, the transverse arm member being secured to the upper and lower arms near their inner ends, and the other of said arms consisting of integral upper and lower wire arm members having their inner ends formed into loops hingedly mounting them on the transverse arm member, the inner ends of the first arm members extending beyond the transverse arm member and being bent to form stop members containing the arm loops so as to limit their motion along and about the transverse member, and a wire suspending-hook adapted to support and lock the arms in expanded position comprising a loop slidable along the transverse arm member, and extensions attached to the loop spaced apart from the transverse arm member and from each other and extending towards the upper arm members, said extensions being adapted to secure the upper stop and arm loop

together when the suspending-hook is slid up the transverse arm member.

5. A garment stretcher comprising a pair of oppositely extending arms, each arm including upper and lower arm members and an upwardly extending serrated member secured to the lower arm members, and a pair of body members, each of said body members being adjustably supported on a lower arm member by loop portions thereof, one loop passing around a serrated member and lower arm member and being adapted to rest in the serrations and the other loop being open and being adapted to pass around the lower arm member, the first loop being substantially bent so that when the second loop is disconnected from the lower arm member the body member hangs loosely and so that the second loop when forced onto the lower arm member clamps the first loop in position on the serrated member.

6. A garment stretcher comprising a pair of oppositely extending arms, each arm including an upper and lower arm member, the lower arm member being of wire, and an upwardly extending serrated plate secured to the lower arm members, and a pair of body members, each of said body members being adjustably supported on a lower arm member by loop portions thereof, one loop passing around a serrated member and lower arm member and being adapted to rest in the serrations and the other loop being open and being adapted to pass around the lower arm member, the first loop being substantially bent so that when the second loop is disconnected from the lower arm member the body member hangs loosely and so that the second loop when forced onto 35

the lower arm member clamps the first loop in position on the serrated member.

7. A garment stretcher comprising a pair of oppositely extending arms, each arm including upper and lower arm members and upwardly extending serrated members secured to the lower arm members, and a pair of wire body members consisting of integral side members joined near their upper ends by a cross member, the upper ends of the side members being formed into loops extending above the cross member, one loop passing around the serrated member and lower arm member and being adapted to rest in the serrations and the other loop being adapted to pass around the lower arm member, the first loop being substantially bent so that when the second loop is disconnected from the lower arm member the body member hangs loosely and so that the second loop when forced onto the lower arm member will clamp the first loop in position on the serrated member.
